RAT GUARD FOR NAVAL SHIPS

Sam Fassman, Brooklyn, N. Y.

Application May 20, 1939, Serial No. 274,738

1 Claim. (Cl. 114—221)

This invention relates to a flat one-piece rat guard device for use onto hawsers or cables to prevent rats boarding naval ships.

The salient feature of the invention is the unique method of securing the diametrical transversed edges of the split or semi-circular metallic sheet members together in a flat, smooth and flush-like finish on the underside from which the rat will try to pass the disk guard which gives the effect of a one-piece disk-guard, thereby making it difficult for the rat to get any footing.

Another salient feature of the invention is a rectangular plate or sheet metal strip member beaded over to provide a channel portion on each side of the central semi-opening and the adjacent cleats of the hinged braces, the rectangular plate members and the transversed edges when interlocked together reinforce the diametrically transversed edges, the flat semi-circular metallic sheet members, together with the hinged braces lashed to the hawser at about a right angle to the plate and cleat members, provide a durable structural form of a rat guard. The cleats 24 provide reinforcement and firmness to that portion where secured to on the flat semi-circular metallic sheet members.

Another salient feature of the invention, is the adaptability of adjusting the semi-circular metallic sheet members onto smaller or larger hawsers or cables other than the standard sizes.

Another salient feature of the invention, is the simplicity in assembling of the complete disk-guard device and securing to the hawser or cable, and its flexible action when in use during heavy winds without weakening the structural parts.

Another salient feature of the invention, is the hinged operation of the semi-circular sheet members which open sufficiently to allow clearance of the hawser or cable to which it is quickly secured and lashed in place.

Other features of the invention will appear as the description proceeds in the following specification, accompanied by the annexed drawing, in which

Fig. 1 is a side elevational view of the flat one-piece rat disk guard device secured to the hawser or cable of the ship.

Fig. 2 is a plan view slightly reduced in scale of that shown in Fig. 1.

Fig. 3 is a plan view similar to Fig. 1, except the semi-disk members are shown opened for the clearance of the hawser or cable to engage the central semi-hole portions where it is to be secured and lashed together as shown in Fig. 1.

Fig. 4 is a much enlarged sectional view of the telescoping method of securing the split or semi-circular members together, taken on line 4—4 of Fig. 2.

Fig. 5 is a similar sectional view taken on line 5—5 of Fig. 2.

Fig. 6 shows in perspective of the two semi-circular metallic sheet members with their corresponding diametrical transversed edges locked together for shipping purposes.

Referring to the drawing, the numerals 1 and 2 designate the generally flat semi-circular metallic sheet members, for example, made of galvanized sheet steel, zinc coated or may be of other glassy-like surface material, and are hinged at 3 into the channel portions 4 formed by the plates or sheet metal strips 5 that are secured to the semi-disk member 2 by rivets as at 7, or if so desired, may be also secured by welding at 6 in Fig. 4. Each semi-circular members 1 and 2 are provided with a central semi-opening 8 and 9 so when they are brought together as shown in Fig. 2, a circular hole is provided to snugly surround tightly the hawser or cable 10 that extends from the ship to the dock, or onto the anchorage cable or chain.

In Fig. 4 an enlarged section is shown of the channel portions 4, in which the rectangular plates or strips 5 may or may not be beaded over at 11 to provide for the channel portions 4, the opposite edge being beaded over at 12, and the halved disk member 2 may or may not be beaded over at 13. A threaded bolt 15 is secured in the member 2 and extends through the rabbet and channel portion 4 and the rectangular plates or sheet metal strips 5, and is provided with a lock or wing nut 16.

Each of the semi-circular metallic sheet members 1 and 2 is provided with braces 21 pivotally hinged to bracket members 22 secured by rivets 23 to the strips 24 and the members 1 and 2. These braces 21 may lie flat as shown in Fig. 3 when the two semi-circular members 1 and 2 are partially swung open on the hinged pivot 3 by unlocking the lock or wing-nut 16 on the cleat 5, said hinge 3 and lock-nut 16 being as close to the outer periphery edge of each member 1 and 2, as may be desired. The periphery edge PE of the semi-disk guard members 1 and 2 is to be very thin or rounded in any suitable manner, so as not to provide any possibility of a rat getting a foothold thereon and so that even if he jumped on the members he would likely slide off.

The hinged brace members 21 are provided

with a looped end 25 forming a hole 26 to slip a lash cord 27 therethrough for securing to the hawser 10, in which the braces 21 incline at about a right angle to the cleats 24 secured 5 onto flat semi-circular metallic sheet members 1 and 2, shown clearly in Figs. 1 and 2. The semi-disk member 1 is slotted at 30 to engage in cooperation the bolt 15 in the channel portions 4 in order to be adjustable to the size hawser or 10 cable 10, varying from 2" to 3" more or less. The diameter of flat-disk rat guard RG shown in Figs. 1 and 2 may also be 24", 30" and 36" more or less.

In Fig. 1 and Fig. 2 the complete device is 15 shown in its attached position on the hawser or cable 10, with the braces 21 and cooperating semi-circular openings 8 and 9 bearing thereon and secured tightly thereto by the lashing cord 27 tied in any suitable knotted manner, as at 32, 20 or secured as otherwise desired.

It is to be noted clearly in Figs. 1, 4 and 5, that 25 the two halved or semi-disk members 1 and 2 when interlocked together into the channel portions 4 in a wedging and binding fit provides a reinforcement for the thin diametrically transversed edges 41 and 41', and also form on the underside U the effect of a one-piece disk and rat guard, which offer no projecting or gripping 30 portions for the rat to get a hold on by his feet, the beaded end 13 of the halved disk member 2 may be fitted almost to a flush connection to the other semi-disk member 1.

In shipping the device, each semi-disk member 35 is released by the lock or wing-nut 40 at the hinged portion 3, and slot 30, and each member is placed onto each other with the diametrical transversed edges 41 in alignment therewith, and locked together by the wing-nuts 15 onto the bolts 15 through the holes 40 and slot 30, the lashing rope 21 and braces 21 interposing between 40 the semi-disk member 1 and 2.

It is to be noted that an extra hole 40' is 45 provided adjacent to the hole 40 in the semi-disk 2, so if it is desired to secure the disk-guard onto a smaller hawser or cable, the halved or semi-circular metallic sheet member 1 may be hinged in this hole 40'.

It is to be further noted that the flat semi-disk member 2 is slightly in advance of the 50 rectangular plate or metal strip members 5 (see Figs. 3 and 4) so as to insert readily and easily the transverse diametrical edges 41 of the semi-disk member 1 into the channel portions 4, and

also the central semi-openings 8 and 9 are beaded or rounded in any suitable manner, over so as not to cut into the hawser rope or cable 10. Also, if desired, the two rectangular plate or sheet metal strip members 5 may be made in one cross piece and wider with a deeper grooved channel or rabbet portion 4, and provided with a similar central opening corresponding to the semi-opening 8.

It is to be noted that the plates 5 and the 10 cleats 24 are in parallel relation to each other thereby reinforcing that particular portion of each flat semi-circular metallic sheet member, while the pair of braces 21, directly opposing each other and at about a right angle to the plates 5 15 and cleats 24, tend to steady each semi-disk member onto the hawser 10.

Furthermore, the open slot 30 may be a slotted 20 hole or holes similar to holes 40 and 40' or other means to lock the two semi-disk guard 20 members 1 and 2 may be adopted than shown as described, just so a smooth and flat-like one piece rat guard is effected.

It is to be understood I do not confine myself 25 to the exactness of parts as shown and described, and reserve the right to alter any part of the invention, if same comes within the scope of the appended claim.

Having thus described my invention what I 30 claim as new and desire to secure by Letters Pat- ent is as follows:

A rat guard of the character described comprising a pair of generally flat semi-circular metallic sheet members having transverse meeting edges, each plate formed to provide a central semi-circular opening therein to engage a cable, plate elements secured on one of said members, the elements being positioned on each side of the opening therein and along said transverse edge to provide channel portions for engagement 40 with the transverse edge of the other member, cleat members secured to said plates in spaced relation to said openings and in approximately parallel relation to said edge, brace elements hingedly attached to said cleats to extend diagonally of the plate for attachment with the cable, and clamping means cooperating with the channel portions to bind the transverse edges together about a cable, the brace elements and clamping 45 means adapted to hold the guard in substantially 50 a right angle relation to the cable.

SAM FASSMAN.
